TABLE LAMP BASE

David T. Emmel, 2301 SE. 8th Court,
Pompano Beach, Fla. 33062

Filed Dec. 30, 1974, Ser. No. 537,783

Term of patent 7 years

Int. Cl. D26—05

U.S. Cl. D48—20 R

FIG. 1 is a perspective view of a table lamp base showing the new design.

FIG. 2 is a side elevational view of applicant's table lamp base.

FIG. 3 is a top plan view of applicant's table lamp base.

FIG. 4 is a bottom plan view of applicant's table lamp base.

The shade and lamp bulb are shown in broken lines in FIGS. 1, 2 and 3 for illustrative purposes only.

I claim:

The ornamental design for a table lamp base, as shown and described.
